UNITED STATES PATENT OFFICE.

ALFRED W. HANINGTON, OF NEW YORK, N. Y.

DESIGN FOR A PILLOW-CASE.

SPECIFICATION forming part of Design No. 26,417, dated December 15, 1896.

Application filed September 28, 1896. Serial No. 607,260. Term of patent 3½ years.

To all whom it may concern:

Be it known that I, ALFRED W. HANINGTON, a citizen of the United States, residing in the city, county, and State of New York, have invented and produced a new and original Design for Pillow-Cases and the Like, of which the following is a specification, reference being had to the accompanying drawing, showing a part thereof.

10 In this drawing the figure thereof represents a perspective view of a sofa-pillow containing my design upon the case thereof.

15 The leading feature of my design consists in the representation of a bicycle-wheel, showing the hub, rim, spokes, and tire thereof, with rectangular panels artistically arranged upon the spokes tied at the corners thereof to the spokes of the wheel by bows of ribbon or the like.

The object of my invention is to provide a 20 design for pillow-cases and other analogous devices. Sixteen panels are arranged in a single bicycle-wheel upon which autographs are intended to be written.

Having now described my invention, what 25 I claim as new, and desire to secure by Letters Patent, is—

The design for pillow-cases and the like, substantially as herein shown and described.

In testimony whereof I affix my signature 30 in the presence of two witnesses.

ALFRED W. HANINGTON.

Witnesses:

J. W. SOATHWARD,
MONROE SONNESCHEIN.
